ABSTRACT: A cable-pressure-equalizing accessory having a cup-shaped member fixed to the outer end of a tubular fitting. The latter is equipped with adjustable split ring means for holding the tubular fitting seated in an opening through a cable sheath in a manner excluding moisture and foreign matter while equalizing the internal cable pressure with the ambient pressure.

PRESSURE-EQUALIZING ACCESSORY FOR CABLES

This invention relates to electrical cables and more particularly to an improved pressure-equalizing accessory readily assembled to a cable sheath to avoid the possibility of a pressure differential between the interior and exterior of the cable.

The accessory has a flanged tubular fitting supporting a gasket with its forward end protruding sufficiently to extend into a cooperating opening in the cable sheath. The accessory is clamped to the cable by a split ring secured to the fitting and embracing the cable snugly. The split ring may be provided with attached adjusting means effective to contract the ring against the cable sheath or with clamping bands assembled over the split ring and tightened. Desirably a plaque of tacky buna material or the like is sandwiched between the sheath and the split ring to safeguard against the entry of moisture.

The outer end of the fitting is provided with a deep cup-shaped shroud member with its open end facing downwardly and enclosing fine foraminous material crosswise of its interior effective to bar the entry of foreign matter. The installed accessory places the interior of the cable in direct communication with the atmosphere thereby avoiding the possibility of a pressure differential between the interior and exterior of the cable despite changing atmospheric pressures and temperatures.

Accordingly the primary object of the present invention is to provide an improved cable pressure-equalizing accessory.

Another object of the invention is to provide simple, inexpensive construction easily installed on cables at intervals and operating to vent the interior of the cables to the atmosphere while excluding foreign material and moisture.

These and other more specific objects will appear upon reading the following specification and claims and upon considering in connection therewith the attached drawing to which they relate.

Referring now to the drawing in which a preferred embodiment of the invention is illustrated:

FIG. 1 is an exploded perspective view of one preferred embodiment;

FIG. 2 is a cross-sectional view of the FIG. 1 embodiment shown installed on a cable;

FIG. 3 is a fragmentary cross-sectional view taken along line 3-3 on FIG. 2;

FIG. 4 is a fragmentary view similar to FIG. 3 but showing a simple modification;

FIG. 5 is a perspective view of another preferred embodiment of the pressure-equalizing assembly per se;

FIG. 6 is a cross-sectional view on an enlarged scale showing the FIG. 5 construction installed on a cable; and

FIG. 7 is a fragmentary sectional view through a further embodiment of the invention.

Referring initially and more particularly to FIGS. 1 and 2 there is shown a typical embodiment of the invention pressure equalizer, designated generally 10. This accessory comprises a tubular fitting 11 having a threaded outer end 12 encircled closely adjacent its rounded forward end 14 with a radial flange 13. A thick gasket ring 15 of neoprene or the like has a snug fit over end 14 and seats against the forward face of flange 13. The rear face of flange 13 supports the inner surface of a plaque of thin sheet metal 17 having a length adequate to form a split ring encircling a cable to which accessory 10 is to be attached with a substantial overlap of its opposite ends. Strip 17, preferably formed of stainless steel or aluminum alloy, is provided with an upstanding flange 19 the internal diameter of which is slightly less than that of fitting 11 at the base of threads 12. It will be understood that strip 17 is forced downwardly over fitting 11 causing the out-turned flange 19 thereof to be expanded slightly as it is forcibly pressed over the enlarged base end of threads 12. The exterior of the fitting at this enlarged portion may be axially scored so that flange 19 mechanically interlocks therewith during assembly.

Applied to the inner side of the split ring member 17 is a plaque 20 of thick tacky material such as buna well known for its durability, sealing and adhesive characteristics. Prior to in-

stallation, its outer surface is preferably protected with a sheet of waxy paper or the like, 21 which is readily peeled away just prior to assembly of the accessory to a cable.

The means shown in FIGS. 1-3 for holding the split ring snugly clamped about a cable of conductors 23, comprises a pair of clamping bands 24, 25 of any well known commercial type having their ends overlapping and adjustable relative to one another by rotation of a screw 26, 27 having its threads engaged with short slots formed crosswise of the clamping band.

10 It will be understood that any suitable type of clamping band may be employed.

Protecting the outer end of fitting 11 against entry of moisture and foreign matter is a deep cup-shaped member 30 having a threaded opening 31 in its bottom mating with threads 12 of fitting 11. The shouldered interior side wall of member 30 supports fine wire mesh or other foraminous material 33 held in place by keeper ring 34 and indentations 35. Cup member 30 may be molded of plastic or formed from light weight noncorrosive metal. In the latter case, it may be protected with an anodized or other suitable coating.

15 The installation of equalizer 10 will be readily apparent from the foregoing description. First a small opening 37 is formed in the sheath 36 of cable 23. Desirably, this opening is formed on the underside of the cable sheath and is sized to receive the forward end 14 of fitting 11. It is important that this end not protrude beyond the inner end of opening 37 as this could interfere with or damage the electrical conductors enclosed by sheath 36.

20 Opening 37 having been prepared, the installer removes the waxy covering 21 from the buna plaque 20 and inserts the leading end 14 of the fitting into the opening and wraps the opposite ends of the split ring forming member 17 about the cable sheath with the longer end overlapping the shorter end.

25 The tackiness of plaque 20 aids very materially in holding the device in place while the clamping bands 24, 25 are being inserted over the opposite lateral edges of ringlet 17. The clamping screws 26, 27 are then progressively tightened pressing the layer of tacky material against the sheath and expanding this material laterally until its outer edges lie substantially even with the adjacent edges of member 17. If the cup-shaped member 30 has not been assembled to threads 12, this is done, thereby completing the assembly operation. The central bore 40 through tubular fitting 11 is in free communication with the interior of the cable sheath and with the atmosphere through the downwardly opening shroud member 30. Any change in pressure conditions between the interior and exterior of the cable are immediately equalized through this passage and member 30.

30 Referring now to the modification shown in FIG. 4, it is pointed out that this embodiment differs from the first-described construction essentially in the use of a threaded nipple 42 to hold shroud member 30' to the internally threaded outer end of fitting 11'. Otherwise, the two embodiments are 35 constructed and installed in the same manner and their similar elements are designated by the same reference characters but distinguished by the addition of a prime.

35 Referring to FIGS. 5 and 6, there is shown a further simple embodiment of the invention, the same or corresponding elements being designated by the same reference characters as the FIGS. 1-3 but distinguished by the addition of a double prime. A principal difference between the FIG. 3 and 4 and the FIG. 5 and 6 embodiment is that the split ring member 17'' is provided with an attached adjustable take up means 26'' so that its overlapping ends can be contracted to clamp device 10'' securely to the cable. Although shroud cup 30'' is shown coupled to tubular member 11'' through the threaded nipple of 42'', it will be understood that the threads in the bottom of cup 30'' may mate directly with external threads on the outer end of member 11' in the manner described in connection with FIGS. 1-3. The tacky plaque 20 described in connection with the prior embodiments may be omitted from FIGS. 5 and 6 if desired and reliance placed on the neoprene or the like gasket 15'' to form a fluidtight seal between accessory 10'' and the rim of bore 37'' in the cable sheath.

Still another embodiment of the pressure-equalizing accessory 10''' is shown in FIG. 7 and suitable for installation on cables 23''' having a metal sheath. The tubular fitting interconnecting the cable and cup 30''' comprises an elbow 11''' threaded at its opposite ends and preferably sealed to the cable sheath by solder 45 or a suitable adhesive. This embodiment may also be installed on cables having a plastic sheath using an adhesive to form a seal with the sheath. The elbow fitting 11''' is installed in one side of a cable in the manner illustrated in FIG. 7 with the open end of shroud 30''' facing downwardly. This mode of installation has advantages under certain operating conditions.

While the particular pressure-equalizing accessory for cables herein shown and disclosed in detail is fully capable of attaining the objects and providing the advantages hereinbefore stated, it is to be understood that it is merely illustrative of the presently preferred embodiments of the invention.

We claim:

1. A cable-pressure-equalizing accessory for safeguarding against a pressure differential across a cable sheath, said accessory comprising a tubular member having a wide radial flange spaced close to one end thereof, a seating gasket supported on said flange and adapted to seat against the exterior rim edge of a hole through a cable sheath, split-ring-forming means embracing said tubular member and bearing against the opposite side of said flange from said gasket and adapted to encircle a cable sheath and including means for clamping said ring-forming means snugly against the exterior of a cable sheath, and a cup-shaped shroud member having an opening through the bottom thereof assembled to and in communica-

tion with the end of said tubular member remote from said gasket.

2. A pressure-equalizing accessory as defined in claim 1 characterized in that said split-ring-forming means is fixed to said tubular member and has said clamping means mounted thereon.

3. A pressure-equalizing accessory as defined in claim 1 characterized in that said cup-shaped shroud member is formed of anodized aluminum and includes means for holding the same detachably assembled to said tubular member.

4. A pressure-equalizing accessory as defined in claim 1 characterized in that said split-ring-forming means comprises a thin flexible metal strip having a thick wide plaque of tacky material on the face thereof adjacent said gasket strongly adherent to said metal strip and to a cable sheath when pressed thereagainst, and said clamping means embracing the opposite lateral edges of said metal strip being disposed to either side of said tubular member and adjustable to clamp said strip and said tacky plaque firmly against the exterior of a cable sheath with one end of said tubular member projecting into an opening through the wall of the sheath.

5. A pressure-equalizing accessory as defined in claim 4 characterized in that said plaque of tacky material has an opening therein sized to seat about the rim of said gasket.

6. A pressure-equalizing accessory as defined in claim 4 characterized in that said cup-shaped shroud member includes fine foraminous material extending crosswise of its interior effective to pass air but barring the passage of foreign matter.
